UNITED STATES PATENT OFFICE.

GEORGE W. DENISON, OF BAY VILLAGE, OHIO.

METHOD OF AND APPARATUS FOR MIXING MATERIALS.

Application filed September 6, 1921. Serial No. 498,889.

To all whom it may concern:

Be it known that I, GEORGE W. DENISON, a citizen of the United States, residing at Bay Village, in the county of Cuyahoga and State of Ohio, have invented a certain new and useful Improvement in Methods of and Apparatus for Mixing Materials, of which the following is a full, clear, and exact description, reference being had to the accompanying drawings.

My invention relates to a method and apparatus for causing intimate mixture of various materials. Stated otherwise an object of my invention is to apply one material to another in such a manner that the mixture shall be perfectly homogeneous and each particle of each material shall be equally affected. As an example of a particular use to which my method may be put, the mixing of clay with water may be mentioned.

The apparatus and method may be employed, however, in mixing various powdered materials together, in mixing powdered material with a liquid, in mixing liquids, or in mixing gases with each other or with any or all of the aforementioned materials.

A distinctive feature of the method is the production of a thin film of material which is thrown into intimate contact with a similar thin film of another material.

Further objects of my invention will be apparent in the course of the following description and the features of novelty will be set out in the claims.

Referring to the drawings in which novel devices are illustrated adapted to carry out my novel method, Fig. 1 is a plan view of such a device; Fig. 2 is a section taken on line 2—2 of Fig. 1; Fig. 3 is a section on line 3—3 of Fig. 2; Fig. 4 is a section on line 4—4 of Fig. 2; Fig. 5 is a section on line 5—5 of Fig. 3; Fig. 6 is a longitudinal section of a slightly different form of device which embodies the principles of my invention and is adapted to carry out my novel method; Fig. 7 is a section showing the rotating disk member and taken substantially on line 7—7 of Fig. 6, but having certain portions of the disk broken away and sectioned to show the outlets therein.

My method in general comprises the separation of material into a fine ribbon, film or cloud, and ejecting such film in close contact with a similar film of another material. The apparatus illustrated for carrying out this method comprises, in general, means for ro-

tating the lower portion of a column of material, thereby separating a film from this lower rotating portion by the use of a revolving knife and the effect of centrifugal force and ejecting the films of the materials in close contact into a receptacle.

Referring particularly to the drawings and to the form of device shown in Figs. 1 to 5, inclusive, the machine illustrated consists of the main casing 10 which is provided with a series of concentric cylindrical partitions forming a series of compartments and having open upper ends 12 by means of which they are adapted to be connected with suitable pipes 13 adapted to deliver material to the various compartments. Adjacent the lower end of these cylindrical compartments there is the rotatable disk 20 which is provided with a series of stepped annular faces 25, 26, and 27, extending transverse to the axis of rotation of the disk. At the outer edge of the annular faces are formed the cylindrical walls 31, 32 and 33 which extend upward adjacent the ends of the cylindrical partitions respectively to form therewith a practically continuous chamber having a rotating end.

Running respectively from the lateral faces 31, 32, 33, of the disk member are the passageways 21, 22 and 23, which lead respectively from the inner, intermediate and outer compartments. The passageways 21, 22 and 23, each project at an acute angle from the walls 31, 32 and 33, respectively, so as to form a knife edge 28 on these cylindrical faces of the disk. These edges are adapted to cut a film of the material from the edge of the rotating mass, as the disk rotates in counter-clockwise direction, as seen in Fig. 3. As will be clearly seen in Figs. 3 and 5, the outlet 22 proceeds outwardly in a horizontal plane to the periphery of the disk, but the outlets 21 and 23 are shown as progressing upwardly and downwardly respectively, as well as radially outward, so that the outlet mouths of each of these passageways lie in the same plane which is perpendicular to the axis of rotation of the disk. This placing of the outlets in the same plane is believed to be a preferable arrangement, the object being to insure the close contact of the films or ribbons ejected from the outlets, as the disk rotates.

In order to provide an adjustment whereby the amount of material fed from each of the compartments may be varied, I provide

adjustable means adapted to vary the distance between the stationary cylindrical partitions, and the faces 25, 26 and 27, respectively. In the device illustrated, this means 5 comprises the sleeves 15 which are threaded on the lower ends of the partitions and it will be evident that by causing these sleeves to project forward into the openings in the disk member that the height of the outlet 10 will be varied, thereby varying the size of the film or ribbon ejected, and also varying the amount of material which rotates with the disk.

15 A dome 18 surrounds the rotating disk and serves to prevent the escape of the ejected ribbons of the material and to direct them into a suitable receptacle 17, which may be attached to a suitable flange 16 on dome 18. This dome may be integral with the casing, as shown, or a separate member.

20 In addition to the pipes 13, I also show pipes 18' connected to each of the compartments. These pipes are adapted for use, if various gases are to be mixed by the use 25 of my machine, in which case, the ends of the outlets 12 may be closed by means such as the plates 19 shown in Fig. 1. Suitable valves may be provided in the pipes 18 to 30 control the flow of the material therein. If it is desired to aerate or mix gases with a material in the compartments, these pipes 18 may be used in conjunction with pipes 13.

35 In order to rotate the lower member 20, I have shown this member as attached at its central portion to a stem 60 suitably journaled in the casing 10 and carrying at its upper end a bevel gear 61, meshing with a bevel gear 62. A pulley wheel 24 which is 40 secured to the shaft of the last named bevel gear is adapted to receive power from a suitable source.

45 In the device illustrated in Figs. 6 and 7, I have shown a single cylindrical casing 40 having an adjustable sleeve 41 on its lower end. I also show the rotating disk 50 adapted to close the end of the cylindrical column in a manner similar to that hereinbefore described. In this form of device, however, 50 which is especially designed for mixing a powdered material with a liquid, I prefer to make the stem 51, to which the disk 50 is keyed, in the form of a tube and having a piping 52 connected to its upper end. The piping 52 is stationary, while the piping 51 must rotate to turn the disk 50.

55 In this form of device which has only two material-holding compartments, I prefer to provide the member 50 with two pairs of outlets 56 and 57, the outlets 56 leading to and communicating with outlets in the lower end of the tube 51 and the outlets 57 communicating with the chamber 59 which forms the lower portion of the cylindrical column 40. These outlets are shown as ex-

tending to the periphery of the disk and having their mouths located in the same transverse plane. The outlets 57 project obliquely from the cylindrical face 60 of the disc so as to form the knife edges 58, which operate in the same manner as the knife edges 28 already described. In this form of device, I also show a dome 42 which is similar to the dome 18. It may be made integral with, or separate from the cylindrical casing 40.

70 It will be apparent that the hollow tubular stem might be used in conjunction with a disk member having a plurality of stepped faces, such as illustrated in Fig. 2, and also that a single outlet may be employed running to the stepped faces, if desired.

75 In the operation of the device, if, for instance, the different columns shown in Fig. 2 are filled with powdered material, it will be seen that the rotation of the lower disk will cause a rotation of a portion of the material in each chamber, which is close to this rotating member. On account of the friction between the particles, the rotation will decrease in the upper portions of the columns and at a short distance above the disk the rotation will cease.

80 On account of this friction, the disks will 85 rotate at a greater speed than the material carried thereon, and upon referring to Fig. 3, it will be seen that if the disk is rotating in a counter-clockwise direction, the result will be that the knife edge will cut a slice or ribbon from the outer edge of the material, as the knife revolves, since the material will be forced outward against the knife edge by centrifugal force.

90 The device illustrated in Figs. 6 and 7, 100 operates in a similar manner, except that there will be two jets of each material thrown into the dome as the disk rotates.

95 In either form of device it will be seen 105 that there is produced a thin film or mist of material, which is closely followed by a similar film or films of other material or materials, which are to be mixed together. Where powdered material is being mixed, the spray may advantageously be made so thin as to cause a thickness corresponding 110 to a single particle of the material, so as to insure the intimate mixing of the materials. When it is not necessary to obtain so thin a film, a thicker film may readily be secured 115 by means of the adjustable sleeves 15, 41.

120 It will be seen, therefore, that I have devised a method for rapidly producing an intimate and homogeneous mixture of materials of various kinds with great speed, 125 and a novel device adapted to carry out this method.

130 While I have described specifically the device embodying the principles of my invention, it is apparent that the novel process might be carried out by many different de-

vices and therefore the foregoing description is to be taken as illustrative of my invention rather than as restrictive of its character and scope.

5 Having thus described my invention, I claim:

1. The method of mixing materials which comprises ejecting a thin film of one material by centrifugal force through a rotat-

10 ing outlet to form an annular band in close contact with a band of dissimilar material also ejected by centrifugal force through a rotating outlet.

15 2. The method of mixing materials which comprises separating the materials into thin ribbons by a separating element rotating at a high velocity and ejecting said ribbons of dissimilar material through outlets in a rotating member by centrifugal force whereby 20 each convolution of ejected material will be superposed upon other convolutions of previously ejected material.

25 3. The method of mixing materials comprising ejecting the materials by centrifugal force through revolving outlets arranged to discharge the materials in contiguous bands of minute thicknesses, thus causing a thorough commingling of the materials being mixed.

30 4. The method of mixing materials which consists in feeding the materials downwardly in columns under the influence of gravity, supporting the columns by a rotating element which is rotating at a greater speed than the lower portions of the column, causing the separation of a ribbon of material from each of the columns by said difference in rotation of the lower portions of the columns and the supporting element, and 35 maintaining the separated ribbons in unmixed relation while ejecting the separated ribbons through rotating outlets by centrifugal force whereby a ribbon of one material is superposed upon and caused to mix with a ribbon of dissimilar ejected material.

40 5. The method of mixing materials which comprises rotating a lower portion of a column of material by a rotating supporting element moving at a speed greater than the rotational speed of the lower portion of the column, causing a separation of a portion of the supporting column by said difference in rotation of the supporting element and the rotating portion of the column and 45 ejecting said separated portion of the column through rotating outlets by centrifugal force into a contiguous relation to a stream of another ejected material.

50 6. The method of mixing materials which 40 comprises rotating the lower portions of columns of dissimilar materials by a rotating element having a speed of rotation greater than the rotational speed of the lower portions of said columns, effecting a 55 separation of ribbons from the materials

by said slippage between the supporting member and rotating portions of the columns, and ejecting said ribbons through rotating outlets by centrifugal force while maintaining the respective ribbons of materials separate whereby each ribbon of material is forced into contiguous relation to each other ribbon of material after being ejected.

7. The method of mixing materials which 75 comprises feeding downwardly a column of material, rotating a lower portion of the column by a supporting member having a speed of rotation which is greater than the rotation of the moving portion of the column, effecting the separation of a ribbon of the material by means of said slippage arrangement and injecting the separated ribbons through rotating outlets by centrifugal force whereby the ribbons may be 80 superposed in the form of circumferential bands.

8. The method of mixing materials which 85 comprises feeding downwardly concentric columns of dissimilar materials by gravitation, rotating the lower portions of said columns by a supporting member which rotates at a speed greater than the speed of rotation of the columns, effecting a separation of material from the bottoms of the 90 columns by said difference in rotation, maintaining said separated portions in unmixed relation and ejecting said portions in continuous streams through rotating outlets by centrifugal force whereby dissimilar materials 95 may be brought into a contiguous relation 100 in the form of superposed concentric bands.

9. In a device of the class described, a plurality of compartments adaptable for the 105 reception of dissimilar materials, a rotatable member having a plurality of compartments corresponding to said material receiving compartments, said rotatable member having passageways leading outwardly 110 whereby material from each compartment may be ejected by centrifugal force from the bottoms of the columns of material contained thereby, means for rotating said member, and a receptacle into which said 115 passageways discharge.

10. In a device of the class described, the combination with a receptacle, of a rotating element having a plurality of outlets adapted to eject jets of material by centrifugal force into the receptacle and thereby form superposed circumferential bands, and means for regulating the flow of material to said outlets.

11. In a device of the character described, 125 a compartment comprising a stationary member and a rotatable bottom member, said stationary member being adapted to retain a column of material flowing downwardly to the rotatable member whereby the 120

- lower portion of the column may be rotated by the rotatable member, and means carried by the rotatable member for separating a portion of the bottom of the column, said 5 rotatable member having passageways for guiding said separated column portions outwardly and having outlets formed therein and associated with said passageways whereby the separated material may be ejected 10 therethrough by centrifugal force.
12. In a device of the class described, a casing having a chamber with an open lower end, a rotatable disk-like member below and adjacent said end, said disk-like member 15 having a passageway communicating with its interior and extending outward to the periphery of the member, and means for rotating said member.
13. In a device of the class described, a 20 casing having a chamber with an open lower end, a rotatable disc closing said open lower end and a material receiving member surrounding the disc, said disc having a passageway extending outwardly to the perimeter thereof terminating in an outlet, 25 said passageway establishing communication between said casing and the receiving member whereby material flowing by gravitation upon said disc member may be ejected 30 through said outlet by centrifugal force.
14. In a device of the class described, a material holding compartment structure having a rotary bottom member, said member having a channel running outwardly 35 from a continuation of the compartment formed in the bottom member, there being a separating edge where the channel leaves the compartment which directs a ribbon of material into the channel.
- 40 15. In a device of the class described, a material holding compartment structure having a rotary bottom member having side walls, said member having an outlet running substantially transversely through said 45 walls from a continuation of the compartment formed in the bottom member, whereby a ribbon of material is directed into the outlet, and a receptacle to receive material from the outlet.
- 50 16. In a device of the class described, a material holding compartment structure having a rotatable bottom member having side walls, said bottom member being provided with a lateral outlet through said 55 walls, said structure including a stationary member extending upward from the bottom member and adapted to hold a stationary column of material above the bottom member, means for rotating said bottom, and 60 means for varying the opening from the compartment to the rotating lateral outlet of the bottom member.
17. In a device of the class described, a stationary material holding member, a rotatable member having a circular recess 65 therein into which the end of the first member projects, said rotary member having a passageway in the rotatable member communicating with said recess and extending to the periphery of the member, said passageway forming an acute angle with the lateral wall of the recess to form a knife edge adapted to direct a thin strip of material into said passageway as the member rotates.
18. In a device of the class described, a cylindrical member, a rotatable member having a cylindrical recess therein, into which the end of the cylindrical member projects, there being a passageway in the rotatable member communicating with said recess and extending to the periphery of the member, said passageway forming an acute angle with the lateral wall of the recess to form a knife edge adapted to direct a thin strip of material into said passageway as the member rotates, and means for adjusting the distance between the rotatable and cylindrical members.
19. In a device of the class described, a plurality of concentrically arranged compartments, a rotary member closing the ends of said compartments and having compartments corresponding to said first mentioned compartments, said rotary member being provided with passageways communicating with each of said compartments and extending outwardly to the perimeter thereof and terminating in outlets whereby rotation of said disc at a high speed will cause dissimilar materials in the respective compartments to be ejected through said outlets by centrifugal force.
20. In a device of the class described, a plurality of compartments, one surrounding another, a rotary end member closing the bottom of each of said compartments and having compartments corresponding thereto, outlet passages formed in the rotary member extending from each of the compartments to the perimeter thereof and terminating in outlets, whereby dissimilar materials contained in the respective compartments may be ejected therefrom by centrifugal force, and a driving member for rotating said rotary member at a high speed.
21. In a device of the character described, a plurality of compartments each having stationary side walls, and rotating end walls, said end walls comprising a rotor, said rotor having outlet passages communicating with the compartments whereby material may be ejected from each compartment by centrifugal force, said passageways being arranged to guide the materials to the perimeter of the rotor in the form of ribbons whereby a commingling of the different materials may be effected by superposition of circumferential bands of centrifugally ejected materials.

22. In a device of the class described, a plurality of compartments having stationary side walls and rotary end walls formed by a rotor member closing the ends of the 5 compartments, said rotor having spirally formed passageways extending outwardly from each of the compartments to the perimeter thereof whereby jets of material from each of the compartments may be ejected by 10 the rotor under the influence of centrifugal force, and means for regulating the capacity of the passageways whereby the amount of material escaping from each compartment into the passageways may be predetermined.

23. In a device of the class described, a compartment comprising a rotatable end member having a lateral passageway terminating in an outlet and a stationary member 20 extending upwardly from the end member and adapted to hold a column of material with a portion thereof adjacent said passageway, and a movable ring at the lower end of the stationary member to force the amount of discharge from the column 25 through said passageway.

In testimony whereof, I hereunto affix my signature.

GEORGE W. DENISON.
